(57) **CLAIM**

The ornamental design for a drink cooler as shown and described.

DESCRIPTION

FIG. 1 is a top right perspective view of the drink cooler of the present invention with an environmental view of a first handle embodiment;

FIG. 2 is a right side view thereof;

FIG. 3 is a left side thereof;

FIG. 4 is a front view thereof;

FIG. 5 is a rear view thereof;

FIG. 6 is a bottom view thereof;

FIG. 7 is a top view thereof;

FIG. 8 is a bottom left perspective view thereof;

FIG. 9 is a top right perspective view of the drink cooler of the present invention with an environmental view of a second handle embodiment;

FIG. 10 is a right side view thereof;

FIG. 11 is a left side thereof;

FIG. 12 is a top view thereof;

FIG. 13 is a bottom view thereof;

FIG. 14 is a front view thereof;

FIG. 15 is a rear view thereof;

FIG. 16 is a bottom left perspective view thereof;

FIG. 17 is a top right perspective view of the drink cooler of the present invention with an environmental view of a third handle embodiment;

FIG. 18 is a right side view thereof;

FIG. 19 is a left side thereof;

FIG. 20 is a top view thereof;

FIG. 21 is a bottom view thereof;

FIG. 22 is a front view thereof;

FIG. 23 is a rear view thereof;

FIG. 24 is a bottom left perspective view thereof;

FIG. 25 is a top right perspective view of the drink cooler of the present invention with an environmental view of a fourth handle embodiment;

FIG. 26 is a right side view thereof;

(Continued)

FIG. 27 is a left side thereof;
 FIG. 28 is a front view thereof;
 FIG. 29 is a rear view thereof;
 FIG. 30 is a top view thereof;
 FIG. 31 is a bottom view thereof; and,
 FIG. 32 is a bottom left perspective view thereof.
 The portions of the drink cooler illustrated in broken lines
 form no part of the claimed design.
